Primary Examiner — Sheryl Lane

(74) Attorney, Agent, or Firm — Global Intellectual Property Agency, LLC; Daniel Enea

(57) **CLAIM**

The ornamental design for a fruit collecting device, as shown and described.

DESCRIPTION

FIG. 1 shows a perspective view of the fruit collecting device;

FIG. 2 shows a top plan view thereof;

FIG. 3 shows a bottom plan view thereof;

FIG. 4 shows a left side elevation view thereof;

FIG. 5 shows a right side elevation view thereof;

FIG. 6 shows a front elevation view thereof; and,

FIG. 7 shows a rear elevation view thereof.

The broken lines represent environment and form no part of the claimed design.
